UNITED STATES PATENT OFFICE

ELWOOD S. BURCH, OF DOWAGIAC, MICHIGAN, ASSIGNOR TO ROUND OAK FURNACE COMPANY, OF DOWAGIAC, MICHIGAN

DESIGN FOR A GAS STOVE

Application filed October 29, 1931. Serial No. 41,561. Term of patent 7 years.

To all whom it may concern:

Be it known that I, Elwood S. BURCH, a citizen of the United States, residing at Dowagiac, in the county of Cass and State of Michigan, have invented a new, original, and ornamental Design for Gas Stoves, of which the following is a specification, reference being had to the accompanying drawing, forming part thereof.

The figure is a front perspective view of a gas stove, showing my new design.

I claim:

The ornamental design for a gas stove, as shown.

ELWOOD S. BURCH.
